UNITED STATES PATENT OFFICE.

BERTHOLD LINDEMANN, OF LOS ANGELES, CALIFORNIA.

SUSPENDED RAILWAY.

1,106,102.

Specification of Letters Patent.

Patented Aug. 4, 1914.

Application filed October 16, 1913. Serial No. 795,439.

To all whom it may concern:

Be it known that I, BERTHOLD LINDEMANN, a citizen of the United States, residing at Los Angeles, in the county of Los Angeles, State of California, have invented new and useful Improvements in Suspended Railways, of which the following is a specification.

This invention relates to a suspended railway, preferably but not necessarily of the mono-rail type; and the invention consists broadly in the arrangement and correlation of the various operating parts so that the load of the traveling cars is evenly distributed to a number of supporting wheels, and so that the supporting rail has this same load evenly distributed over it. This is the feature which I wish to particularly emphasize in the application. There are several features of construction of more or less importance; but this feature of arrangement for even distribution of the weight and load is the feature I wish to herein particularly describe and claim.

In a suspended system of this character, it is usual that the rail or rails be in the form of beams; the span of the rails between adjacent supports being a quantity fixed after consideration of the loads to be carried and the weight of materials desired to be employed. Ordinarily, the cars of suspended systems are carried on one or two hangers and the weight of the cars is concentrated at one or more points on the beam rail. Concentration of the load makes it necessary to support the rail at very short intervals and makes the construction heavy, complicated and expensive.

It is one of the objects of my invention to obviate a complicated and expensive construction and to substitute therefor a simple, light-weight structure which will efficiently support the trains traveling over its tracks. I am enabled to accomplish this object by the fundamental expedient of distributing the load of each car evenly over the track; so as to form in effect an evenly loaded beam. It is well known that a beam evenly loaded will carry about twice as much weight as a beam loaded with a concentrated weight. By such an expedient, I can either decrease the weight of the rails per linear foot or I may increase the span; or, using intermediate weight and spans, I may greatly lessen the deflection of the rails

due to the weight of a passing train. It is especially desirable that the rails be kept as nearly as possible in the same horizontal plane; that there be no undue deflection of the rails under the weight of the train. All of these features I am enabled to efficiently carry out in practice by distributing the load of a train or of a single car over one or more spans of the rail. It may preferably be that the distance over which I distribute the weight of a car shall be an even multiple of a rail span; but this is not necessarily the case, as will hereinafter be pointed out.

I have illustrated preferred forms of my invention in the accompanying drawings, in which,

Figure 1 is an elevation illustrating my improved system, Fig. 2 is a side elevation of the truck, Fig. 3 is a plan of a preferred form of truck which may be used in carrying out my invention, Fig. 4 is a vertical cross section taken on line 4-4 of Fig. 2, Fig. 5 is a vertical cross section taken on line 5-5 of Fig. 2, Fig. 6 is a section showing a preferred form of wheel which may be used in carrying out my invention, Fig. 7 is a side elevation of the same.

It will be understood that there are several features shown in these drawings and to be hereinafter explained which I do not herein particularly claim; such particulars including the specific construction of the trucks and wheels. These constructions are only included in this description in so far as they coöperate to carry out my main object as hereinabove set forth, and for the purpose of showing a practical means of carrying my invention into effect.

In the drawings the numeral 10 may designate towers or other suitable supports upon which I mount my rail or rails 11. In the preferred form of trackage I use a base beam 12 surmounted by a channel 13 in which the wheels 14 are adapted to run. These wheels 14 may be of the general type and may coöperate with the rail in the general manner set forth in my application S. N. 733,241 filed November 25, 1912 on traction device; but this is not a necessary feature of my present invention.

It is primary feature of my invention that the wheels 14 are spaced apart above each car 15 and along the track 11 so as to distribute the weight of each car evenly

between the several wheels and so as to distribute the load evenly over the track. The cars 15 may be directly hung on hangers 20 which extend to a point above the rail 11 and pivotally connect at 21 with the main truck frame 22. The main truck frame 22 may be composed of two longitudinal members 23 and transverse members 24 and 25. Transverse members 24 and 25 form the means of pivotally connecting the main truck frame with the individual truck frames at the pivot points 26. Each individual truck frame 27 is pivoted at 26 to the main truck frame, the main truck frame being thereby supported on the two individual frames. The individual frames 27 each carry two wheels 14, propulsion motor 28 and suitable braking apparatus 29. The whole arrangement is such that the wheels 14 are preferably situated equi-distant from each other; and the two or more truck sets of a car are preferably arranged so that there is this same distance between the adjacent wheels of adjacent sets; the truck sets being arranged with respect to the car so that the weight of the car is borne equally by each of the sets; in other words, the hangers 20 preferably support equal partial weights of the car, and the weight upon each hanger will be distributed equally to the several wheels of each truck set.

The wheels themselves may be of any desired construction; they may be of any suitable material and may engage the rails in any manner; but certain forms are to be preferred. In Figs. 6 and 7 I have shown a preferred form of construction wherein each wheel 14 has a hub 30 and side flanges 31. Spokes or segments 32 abut or, nearly, abut the hub and are confined between the side flanges. Bolts 33 hold the construction together laterally, while annular flanges 34 fitting into corresponding depressions in the segments may hold the segments from longitudinal or radial movement. In the spaces between each of the segments 1 may place sheets of resilient material, such as rubber or equivalent, shown at 35. These resilient sheets are held tightly between the adjacent segments and form resilient backings for each of the segments, allowing each of the segments to move slightly inwardly by a sort of wedging action and to compress the rubber sheets against the adjacent segments. For this purpose the segments may not be directly against the hub 30. The segments themselves may be of wood, metal, fiber or any other suitable material; and the wheels will have a peripheral shape to run in the channel 13 or in the groove otherwise formed for the rail. This is one of several improved means for attaining the end of a resilient wheel-and-track combination.

It has been explained how the weight of

each car is evenly distributed between the several supporting wheels, and how the weight of a car or train is evenly distributed over the track. In Fig. 1 I have illustrated a train on a track; and in this figure 70 I show how the weight of a train may be distributed over several succeeding spans of the track. I have illustrated the weight of one car being distributed practically over two spans of track. Supposing that each 75 car weighed five tons, in this case each span of track would be subjected to a uniformly distributed load of two and one-half tons. This would be the case whether a large number of cars composed a train or whether 80 the train was composed of one car. Supposing now, that the spans were increased in length to be equal to two cars; then each span would be subjected to, and would necessarily be capable of supporting a uniformly distributed load of ten tons. In any case, the maximum load to which any span of track would be subjected would be the weight of all the cars which could be placed in a span, said weight being evenly distributed over the span. This is true whether the span is longer or shorter than one car. In case the span is longer than one car, then the span would always be capable of carrying the semi-concentrated and semi-distributed load due to one car passing over it; for it would be capable of carrying this one car together with as many other cars as could be placed in the span. A one car load would be the minimum load of a span; 100 the maximum load would be the weight of as many cars as can be placed in a span. The track is designed to efficiently carry its maximum load evenly distributed.

I claim—

1. A suspended railway system, comprising in combination a rigid overhead rail, supporting means for the rail at constant intervals so that the rail is uniformly supported as a continuous beam, a car, and multiple wheeled trucks from which the car is suspended, the wheels of the trucks bearing on the rail at points separated by approximately equal distances along the rail, and the weight of the car being evenly distributed between the several wheels, so that the weight of the car is uniformly longitudinally distributed over the rail, substantially as described.

2. A suspended railway system, comprising in combination a rigid overhead rail, supporting means for the rail at constant intervals so that the rail is uniformly supported as a continuous beam, a car, and multiple wheeled trucks from which the car is suspended, the wheels of the trucks bearing on the rail at points separated by approximately equal distances along the rail, the distance between points of bearing of the two outermost wheels being approxi- 130

mately not less than the distance between adjacent supports for the rail, and the weight of the car being evenly distributed between the several wheels, so that the weight of the car is uniformly longitudinally distributed over at least one span of the beam rail, substantially as described.

In witness that I claim the foregoing I have hereunto subscribed my name this 6th day of October 1913.

B. LINDEMANN.
